UNITED STATES PATENT OFFICE.

WILLIAM CLINTON BROWN, OF SYRACUSE, NEW YORK, ASSIGNOR TO EDWARD N. TRUMP, OF SYRACUSE, NEW YORK.

COMBUSTION SYSTEM.

1,326,642.

Specification of Letters Patent. Patented Dec. 30, 1919.

Application filed June 22, 1917. Serial No. 176,293.

To all whom it may concern:

Be it known that I, WILLIAM CLINTON BROWN, a citizen of the United States, residing at Syracuse, in the county of Onondaga, State of New York, have invented new and useful Improvements in Combustion Systems, of which the following is a specification.

My invention relates to improvements in combustion system for liquid fuel. The object is to provide improved method and means for securing the proper feed of air and fuel and the proper ratio of same.

Referring to the drawings which illustrate merely by way of example, suitable embodiment of my invention—

Figure 1 is a diagrammatic view in section.

Fig. 2 is a detail in elevation of the adjusting device.

Fig. 3 is a plan view of the plunger pump.

Similar numerals refer to similar parts throughout the several views.

The fan or blower 5 delivers air from the channel 6 through the conductor 7 to the fire box or combustion chamber 8 beneath the boiler. This air is preferably passed over the hot surfaces of the portion of conductor 7, which extends beneath the fire box and contiguous thereto and then upwardly with a reverse turn to deliver thereto, as shown in Fig. 1, so that said portion of the conductor is subject to the heat of the fire box, in order to warm the air before it is delivered to the fire box.

The blower 5 is driven by any suitable means not shown. The shaft of the motor is connected by the beveled gear 9 with the shaft 10 carrying the actuator plate 11 for actuating the plungers 12 of the fuel pump 13. This pump delivers fuel from the reservoir 14 through tubing 15 to the fire box 8 or into the air conductor leading thereto. It is also preferable to have this tubing 15 pass through a heated zone provided by the portion of conductor 7 which is contiguous to the fire box, as above described, before delivering into the fire box, so that the liquid fuel will either be gasified or partially gasified before being introduced into the fire box and it shall preferably be sprayed into the air at or near the entrance to the fire box, so there will be no danger of the flame working back into the air duct.

In order to vary the amount of heat in the fire box means are provided for reducing the amount of air supplied thereto, and also means for reducing the supply of liquid fuel. It is usually desirable that these means be automatically controlled and also that these varying means be so connected together that they will vary in proper proportion to maintain a proper combustible mixture when varying the amount of heat required.

When used in connection with steam boilers this varying apparatus may be operated by the steam pressure or by the temperature of steam or by both, in order that the combustion may be properly proportioned to maintain a fixed steam pressure or temperature under a varying demand.

As an example of such automatic regulation device, I have provided the cylinder 35 connected by pipe 36 with a suitable steam pressure or temperature controlled device not shown. In cylinder 35 is operated the piston 37 under the influence of spring 38. Piston 37 is provided with rod 39 which is pivotally connected at 20 with the lever 21. This lever 21 is mounted on the fulcrum 22 which is arbitrarily movable and adjustable with respect to said lever 21, by means of the following mechanism; the fulcrum 22 comprises the trunnioned sleeve 22' 85 slidable on lever 21. The trunnions are mounted in the bracket 17 which is movably mounted on frame 18 and is provided with a threaded lug 17' engaging with the screw 19 provided with the hand wheel 19'. When it is desired to shift the sleeve 22' either to the right or the left on lever 21, one of the lock nuts 16 is moved away from the sleeve and the screw 19 is turned in the required direction to shift the sleeve and fulcrum on lever 21 as desired, whereupon the lock nuts are made tight on each side of sleeve 22' to maintain said position of adjustment. The valve 23 in air duct 6, is provided with a lever 24 connected by rod 25 with the lever 21 between the fulcrum 22 and the pivot connection 20.

The plate 11, while rotatable with shaft 10, has a rocking or pivotal connection with said shaft. This plate 11 is connected at a point near its outer periphery by the link 26 with a collar 27 slidably mounted on shaft 10. The lever 28 is pivotally mounted

at 29 on a fixed support, one end engaging with the collar 27 while the other end is connected by the rod 30 with the end of lever 21 on the right hand side of the fulcrum 22. 5 In operation we may assume the parts to be in the position when the steam pressure is high, and it is desirable to reduce the temperature in the fire box by cutting down the supply of fuel. The pressure of the boiler 10 communicated through pipe 36 maintains piston 37 against the actuation of spring 38 in such position as will close or nearly close the valve 23 as desired, while at the same time the plate 11 is correspondingly held in 15 such position that in its rotation with shaft 10 it will fail to actuate or only slightly actuate the pump plungers 12. It will be understood that when the plate is held in a horizontal position it will be neutral, that is, 20 rotate without actuating the plungers, and the more it is tilted out of the horizontal the greater will be the degree of actuation of the pump plungers.

Thus as the steam pressure in the boiler 25 varies the supply of air and fuel to the fire box will be correspondingly and automatically varied.

In order to secure the proper proportion or ratio of air and liquid fuel for any particular condition, the position of fulcrum 22, with respect to the connecting points of rods 25 and 30 with lever 21 is adjusted in the manner above described, thus controlling the relative actuation of the air valve and

fuel pump as desired. When once this adjustment is secured the proportion or ratio is always maintained throughout the range of the automatic control, that is, until the fulcrum 22 is again moved. 35

What I claim is:—

1. In a combustion system the combination of a fire box, a conductor for delivering air thereto, a valve in said conductor, a blower connected with the conductor, a liquid fuel supply and conductor leading 45 therefrom and delivering to the fire box, a fuel pump connected with said conductor, a controlling mechanism for said pump, a pivoted lever having operative connection with the air valve and fuel pump controlling 50 mechanism, and pressure responsive means for operating the lever.

2. The combination recited in claim 1 in which are provided means for arbitrarily adjusting the fulcrum of said lever relatively to the points of connection with the air valve and fuel pump controlling mechanism. 55

3. The combination recited in claim 1 in which are provided means forming heated 60 surfaces over which the air passes before it is delivered to the fire box.

4. The combination defined in claim 1 in which are provided means forming a heated zone through which a portion of the liquid 65 fuel conductor passes before delivering to the fire box.

WILLIAM CLINTON BROWN.
